GEORGE H. FORSYTH, OF CHICAGO, ILLINOIS.

METHOD OF FORMING DISK WHEELS.

1,399,951.

Specification of Letters Patent. Patented Dec. 13, 1921.

Application filed November 10, 1919. Serial No. 336,780.

To all whom it may concern:

Be it known that I, GEORGE H. FORSYTH, a citizen of the United States, residing at Chicago, in the county of Cook and State of Illinois, have invented certain new and useful Improvements in Methods of Forming Disk Wheels, of which the following is a specification.

My invention relates to an improved method of forming disk wheels and other circular disks from steel sheets, and is particularly adapted to the forming of such wheels having a taper cross section, that is to say, progressively decreasing in thickness from the hub to the periphery.

Heretofore it has been usual to blank a disk of suitable size from a large sheet, punch a central hub orifice and then by means of a pressing die to form hub and rim flanges and dish the same more or less as may be wished. This involves a great waste of metal. Where it is desired to produce a wheel of taper cross section, it was usual to grind or mill the same at an immense labor cost and the production of an inferior open-pore disk.

It has been proposed to take a sheet or strip of metal, bend it at right angles to the plane thereof to form a cylinder, weld the ends together, and then expand one end of the cylinder by rolling to gradually change the cylinder to disk form, thus at the same time producing by the rolling action a reduction in thickness of the expanded edge and a resultant taper cross section. This method necessitated a number of successive operations, as the rolling expansion or stretching of the metal after welding is exceedingly difficult to effect without a rupture of the weld.

By my improved method, a reversal of the procedure last referred to, the sheet is bent in the plane thereof to a disk form by rolling and thus expanding one edge of the sheet and, if desired, concurrently turning over each edge to form hub and rim flanges, then welding the adjacent edges and, if found then desirable, subjecting to a truing die. Thus I form the sheet into a disk and in the same operation preferably taper the disk radially and form the hub and rim flanges, all before welding, whereby the disk wheel is formed most economically, of taper cross section, and with no danger of breaking the weld.

In order that the method thus outlined may be more readily comprehended, I have,

in the inclosed drawing, illustrated diagrammatically the several steps of the operation. The drawing is not to be understood as illustrating the best form of apparatus for carrying out the method which is not dependent in any way upon the particular form of mechanism employed. 60

In the drawing—

Figure 1 is a side elevation of the disk 65 partially formed;

Fig. 2 is a conventionalized end view of Fig. 1;

Fig. 3 illustrates the disk after forming and ready for welding; 70

Fig. 4 shows the disk in a truing die, designed to render the same slightly dished or concavo convex;

Fig. 5 is a modified form of disk in the shape of an incomplete annulus; 75

Fig. 6 represents the disk of Fig. 5 after the edges are welded to produce a slightly dished disk or one of conicular form; and

Fig. 7 illustrates the last mentioned disk associated with a truing die. 80

Having reference to the drawings for exemplification, a sheet 11 of suitable cross section of strip form is passed between the rollers 12 whereby one edge of the same is expanded so as to produce a taper cross section 85 as indicated at 11^a. In order to produce a hub flange 13 and a rim flange 14 the roller 15 is arranged to bear upon one edge of the sheet and the roller 16 upon the opposite edge. The passing of the sheet between the 90 rollers 12—12 and the consequent stretching of one edge thereof results in the bending of the sheet in its plane to form a disk 17, as will be readily understood. If the metal is chosen of a length to form the complete disk 95 the result will be that shown in Fig. 3, whereas if the metal is of slightly less length it will be that shown in Fig. 5. In the former case the two edges 17^a and 17^b are in juxtaposition and approximately in contact as illustrated in Fig. 3; in the latter case, the edges 17^a and 17^b are more widely spaced apart as shown in Fig. 5. 100

The edges 17^a and 17^b of Fig. 3 being welded, the result is that of a plain disk such 105 as that illustrated in Fig. 4 which may be utilized in the shape as shown or placed in a forming die as illustrated in said figure and brought to a concavo-convex or slightly dished form. 110

The edges 17^a and 17^b of Fig. 5 being welded, the result is a disk concavo-convex

or dish form such as is shown in Figs. 6 and 7 which by means of the die shown in the latter figure only requires truing to overcome any slight inaccuracies.

5 It will be observed that by my improved method, the sheet 11 of uniform cross section is in one continuous operation formed into an annulus of taper cross section and with or without hub and rim flanges as may 10 be desired. The disk is thus completely formed and tapered in cross section prior to welding whereby any danger of breaking of the weld is obviated. The operation is an exceedingly inexpensive one. There is 15 practically no waste of metal. The resultant disk is accurately formed and without any breaking down of the metal structure as results from the prior art method.

While I have shown the disk rolled into 20 the flat and then formed into the shape desired as by dies, it must be obvious that the rolls could themselves be so formed upon their bearing surfaces as to form the metal disk into final shape, or the disk could 25 be formed into the final shape desired by another set of rolls instead of the dies shown. In other words, the disk might be formed into substantially its final shape during the producing of the disk and before welding, 30 or could be formed into its final shape after welding.

While I have referred to the metal from 35 which the disk is formed as a sheet, it must be evident that the same might be a strip or bar of any suitable dimensions, and it must also be evident that the disk could be formed into any desired cross section, either before or after welding, and by any suitable means for this purpose without losing the advantage already mentioned of 40 producing a disk of whatever form with the least possible waste of material.

I claim:

1. The method of forming disk wheels 45 from sheets of metal which consists in bending the sheet in the plane thereof to form an annulus and simultaneously to cause progressive expansion of the same toward the periphery whereby to taper the cross section.

2. The method of forming disk wheels from sheets of metal which consists in bending the sheet in the plane thereof to form an approximately flat annulus and there- 50 after welding the adjacent ends of the annulus.

3. The method of forming disk wheels of taper cross section from sheets of metal of uniform gage which consists in bending the 60 sheet in the plane thereof to form an approximately flat annulus and to cause progressive expansion of the same toward the periphery whereby to taper the cross section, and then welding the adjacent ends 65 of the annulus.

4. The method of forming disk wheels of taper cross section from sheets of metal of uniform gage which consists in bending the sheet in the plane thereof to form an approximately flat annulus and to cause progressive expansion of the same toward the periphery whereby to taper the cross section, and in the same continuous operation laterally bending the edges of the sheet to form hub and rim flanges, and then welding 75 the adjacent ends of the annulus.

5. The method of forming disk wheels of taper cross section from sheets of metal of uniform gage which consists in bending the sheet in the plane thereof to form an approximately flat annulus and to cause progressive expansion of the same toward the periphery whereby to taper the cross section, and in the same continuous operation laterally bending the edges of the sheet to 80 form hub and rim flanges, and then welding the adjacent ends of the annulus and finally subjecting the disk to a truing and shaping die.

6. The method of forming dished disk 90 wheels from metal strips which consists in bending a strip substantially in the plane thereof to form an annulus having a segment gap and welding the adjacent ends of the annulus to form a dished disk. 95

7. The method of forming disk wheels from metal strips which consists in bending a strip into an annulus and in the same continuous operation forming the central and peripheral portions of said disk into any de- 100 sired shape relative to the plane of the annulus.

8. The method of forming disk wheels from metal strips which consists in bending a strip substantially in the plane thereof to 105 form an annulus then welding the adjacent ends of the annulus, and finally subjecting the disk to a forming die to vary the plane thereof.

9. A method of forming disk wheels from 110 strips of sheet metal which consists in bending the sheet in the plane thereof to form an annulus of the desired contour and thereafter joining the adjacent ends of the annulus.

10. A method of forming dished disks from a flat strip of metal which consists in bending the same and joining the adjacent ends to form an annulus and then subjecting concentric portions of the metal to de- 120 forming stress whereby to vary the original contour of the annulus.

In witness whereof I have hereunto signed my name in the presence of two subscribing witnesses.

GEORGE H. FORSYTH.
